UNITED STATES PATENT OFFICE

ROBERT S. YOUNG, OF NEW BRIGHTON, NEW YORK

HOLDER FOR PAPER SLIPS

Application filed January 20, 1930. Serial No. 422,210.

This invention relates to a holder for paper slips.

In banks, corporation offices and the like employing adding machines it is common practice to use such machines in adding a series of amounts each taken from a narrow slip of paper. For instance a bank acting as issue and transfer agent for a corporation's stock may have each transaction showing the number of shares of stock recorded on a slip of paper six or seven inches long and about one and one-fourth inch wide. In adding the numbers from these slips it is customary for the adding machine operator to grasp a bunch of the slips in his left hand and turn them over, one by one, with the thumb and forefinger of that hand, his right hand being used to operate the adding machine. This method of handling such slips is slow, awkward and leads to errors through omissions by turning more than one slip at a time or by allowing one or more slips to fly back after being recorded on the adding machine.

The important object of this invention is to provide an improved holder arranged to grip one end of a bunch or pack of said slips securely and to hold the slips in such position that the item or items to be added will be plainly visible at the other end, the item bearing ends of the slips being so held and supported that a single rubbing movement of a finger from what may be termed the free end of the top slip of the pack toward the clamped end will effect turning of that slip to expose the item on the slip below and will at the same time separate the turned slip from those unlisted, so that it cannot fly back to rejoin the unlisted slips, the arrangement also being such as to permit turning of one slip at a time.

While the foregoing has referred to stock issue and transfer slips it will be readily appreciated that the device is adapted for handling other slips requiring listing on an adding machine, such as weight slips, checks and the like.

With the above and other objects in view, the invention consists in general of certain novel details of construction and combina-

tions of parts hereinafter fully described, illustrated in the accompanying drawings and specifically claimed.

In the accompanying drawings like characters of reference indicate the parts in the several views, and:—

Figure 1 is a plan view of the device.

Figure 2 is a side elevation thereof.

Figure 3 is a section on the line 3—3 of Figure 2.

Figure 4 is a section on the line 4—4 of Figure 2.

In the embodiment of the invention as here disclosed there is provided a frame of heavy wire having parallel sides 10 and a cross piece 11 connecting respective ends of the sides. The other ends of these sides are provided, as at 12, with means for securing the device to a suitable fixed object such as metal plate or bracket 13 having spaced holes to receive these ends, and here indicated in dotted lines as the same forms no part of the invention. A bridge 14 spans the space between the sides 10 in spaced relation to the cross end 11 and this bridge has tubular sleeves 15 surrounding said sides to support the bridge in proper position. Projecting from this bridge is a light spring tongue 16 which extends beneath the cross end 11.

A second bridge 17 having similar sleeves 18 is supported on the sides 10 adjacent the ends 12. This bridge has at its rear edge a down turned flange 19 provided with in-turned side edges 20 to form opposed channels for the reception of a slide 21 having a forwardly projecting jaw 22 at its upper end, this jaw overhanging the bridge 17. An eye 23 projects forwardly from the lower edge of the slide to receive a rod 24 surrounded by a spring 25 which bears at one end on the bridge 17 and at its other end on said eye so as to urge the jaw 22 toward said bridge.

This spring is strong enough to effectively cause firm clamping of a bunch of slips, the outline of which bunch is shown by the dotted lines 26.

In use a bunch of slips are arranged in a stack with their butt edges flush with each other. This bunch is then taken in one hand

and the jaw 22 raised with the other hand, the butts of the strips are now placed beneath the jaw 22 and the jaw allowed to move back and clamp the slip ends firmly against the bridge 17. The remaining ends of the slips are now passed beneath the cross end 11 to be pressed lightly against this cross end by the spring 16. Now, by passing a damped finger over the top slip from right to left the right end of the slip will be withdrawn from beneath the wire 11 so that it will turn easily to the left. Obviously, it cannot get back beneath the wire by accident so that duplication of the item on the slip is obviated.

15 There has thus been provided a simple and efficient device of the kind described and for the purpose specified.

16 It is obvious that minor changes may be made in the form and construction of the invention without departing from the material principles thereof. It is not, therefore, desired to confine the invention to the exact form herein shown and described, but it is desired to include all such as come within the 25 scope claimed.

Having thus described the invention, what is claimed as new, is:—

1. A device of the kind described consisting of a frame having a pair of sides and a 30 cross end, a bridge member connecting said sides in spaced relation to said end, a clamp adjacent the other end of said frame, said sides being spaced to permit passage of a bunch of slips therebetween to extend below 35 the cross end, and means to press the bunch of slips lightly against the cross end.

2. A device of the kind described consisting of a frame having a pair of sides and a cross end, a bridge member connecting said 40 sides in spaced relation to said end, a clamp adjacent the other end of said frame, said sides being spaced to permit passage of a bunch of slips therebetween to extend below the cross ends, and a light spring finger extending from said bridge beneath said cross 45 end.

3. A device of the kind described consisting of a frame having a pair of sides spaced to permit passage of a bunch of slips and 50 having a cross end, a bridge between said sides spaced from said end, a second bridge adjacent the remaining end of the frame, a clamping jaw movable vertically toward and from the second bridge and located above the 55 same, a strong spring urging said clamping jaw towards the second bridge, and means to press the bunch of slips lightly against the cross end.

4. A device of the kind described consisting of a frame having a pair of sides spaced to permit passage of a bunch of slips and having a cross end, a bridge between said sides spaced from said end, a second bridge adjacent the remaining end of the frame, a clamping jaw movable vertically toward and from 60 65 70 75 80 85 90 95 100 105 110 115 120 125 130

the second bridge and located above the same, a strong spring urging said clamping jaw towards the second bridge, and a light spring finger extending from said bridge beneath said cross end.

In testimony whereof I affix my signature.

ROBERT S. YOUNG.
